United States Patent Office.

JOSEPH LIEBHABER, OF BLESS, BAVARIA.

Letters Patent No. 76,928, dated April 21, 1868.

IMPROVEMENT IN CHURNS.

The Schedule referred to in these Letters Patent and making part of the same.

TO ALL WHOM IT MAY CONCERN:

Be it known that I, JOSEPH LIEBHABER, of Bless, in the Kingdom of Bavaria, have invented a new and useful Improvement in "Churns;" and I do hereby declare that the following is a full and clear description of the same, reference being had to the accompanying drawings, making a part of this specification, and in which—

Figure 1 is a sectional elevation of my churn, showing the inside arrangement.

Figure 2 is a cross-sectional elevation of the same.

The nature of my invention is to provide a churn of such a construction as to have all its parts accessible to easy and thorough cleaning.

To enable others skilled in the art to make and use my invention, I will now proceed to describe its construction and operation.

A A is the body of my churn, made of any suitable wood or material, as ornamental as may be desired outside, but shaped inside as shown by line B C D E.

B T, B' T', B'' T'', B''' T''', are the beaters, set together in the usual way.

Beaters B' T' and B'' T'' are made of two strips of wood, S W, S' W', set apart, as shown in fig. 2. Beater B T is made of one solid board, S B, while beater B''' T''' is made of one board, O B, perforated with circular holes, C H, in number to suit.

The shaft S H holds the beaters in proper place, in the usual way.

A crank, C R, is keyed on its outer end, while its inner end is provided with a thread, screwing into a female screw, F S, on beaters.

The end of the shaft S H sets into a metallic socket, S K, fastened on the inside of the side of body A of my churn, said socket being the journal-box into which shaft S H revolves.

When I want to use my churn, I take hold of one of the beaters, and I screw shaft S H as far as it will go. Then I let go the beater I was holding firm, and, acting on crank-handle C R, I will revolve the beaters from right to left, without danger of loosening shaft S H, since I revolve in the same direction I was screwing.

Again, when I want to take my churn apart, to clean or wash it, I do take hold again of one of the beaters, unscrew the shaft S H, withdraw it, and then take the beaters out, thus allowing access to the sides and bottom of my churn.

My object in constructing my beaters as above described is obvious.

S B, a solid board, strikes the cream, and gives it a movement which drives the whole mass of it against the other beaters, which, composed either of bars set apart, or of perforated boards, divide the cream, and beat it thoroughly in all its parts.

I will assign no space of time in which the butter can be obtained, as I consider, as well as all farmers, that if a good churn, well and sensibly contrived, will help towards obtaining the butter speedily, yet the main depends entirely on the quality of the cream itself.

In the above description, I have shown the crank-handle keyed directly on the outer end of shaft S H; but, when a churn of the kind above described is to be made of large dimensions, I reserve the right to key on the outer end of shaft S H a cog-wheel, on which a pinion would act by means of a driving-crank handle, thus rendering the operation easier to the operator.

Said gearing is indicated in red lines on fig. 1.

I need scarcely add that my churn is closed by a lid, bearing on its centre a small hole, as usual.

Having thus described my invention, what I claim as my invention, is—

The combination of four or more beaters of different construction, for the purpose above set forth and described.

JOSEPH LIEBHABER.
